CLAIM

The ornamental design for an interactive device, as shown and described.

DESCRIPTION

FIG. 1 is a perspective view of an interactive device in accordance with the design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken line is for illustrative purposes only and forms no part of the claimed design.
